UNITED STATES PATENT OFFICE.

WILLIAM R. WILBER, OF THERMOPOLIS, WYOMING.

UNDERREAMER.

Application filed May 17, 1923. Serial No. 639,545.

To all whom it may concern:

Be it known that I, WILLIAM R. WILBER, a citizen of the United States, residing at Thermopolis, county of Hot Springs, and 5 State of Wyoming, have invented certain new and useful Improvements in Underreamers; and I do declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates to improvements in under-reamers of the type used in drilling oil wells.

In the drilling of deep wells, it is essential that casings shall be inserted into the well 20 at least as far as bedrock so as to keep the walls from caving in and to keep water from entering the well. In order to insert the casing into the well, it is necessary to ream the opening below the casing so that it will 25 be at least as large in diameter as the casing. It is, of course, necessary that the underreamer shall be of a larger diameter than the inside of the casing and the reamer must, of course, be inserted and removed 30 through the casing. This makes it necessary that the reamer shall be expandable so that it may be introduced and removed.

I am aware that many different kinds of 35 under-reamers have been made. Most of them, however, have the cutters held in expanded position by means of springs or by other means which leave openings which permit the mud to enter and clog the parts to such an extent that it is difficult to remove 40 the tool.

It is the object of this invention to produce an under-reamer that shall be so constructed that it can be readily collapsed and held in collapsed position for the purpose 45 of inserting the same into a casing, and which will automatically expand to operative position when the reamer reaches the under side of the casing.

It is a further object of this invention to 50 produce an under-reamer in which the cutting lugs shall be held in expanded position by means of a wedge or block that automatically moves into position between the cutter lugs as soon as the reamer reaches a position 55 below the casing.

In order to be able to withdraw the

reamer, it is, of course, essential that the block or wedge shall be removed from its position between the cutters so as to permit them to collapse in order that the reamer 60 may enter and pass through the casing and it is my object to so construct the reamer that this will automatically take place whenever the reamer is pulled upwardly into the 65 casing.

It is a further object of this invention to so arrange and construct the parts that the cutters shall rest securely on the body portion of the reamer so that the shocks and jars will not cause any undue strains on their 70 pivots. I also provide the cutters with lugs which co-act with notches in the body portion to prevent the pivots from being sheared when the cutters are subjected to strains in the operation of removing the reamer.

75 The above objects and others, which will appear as the description proceeds, is attained by means of a construction which I will now describe in detail, reference for this purpose being had to the accompanying 80 drawing in which the preferred embodiment of the reamer is shown, and in which:

Fig. 1 is a longitudinal section of my 85 reamer, taken on line 1—1, Fig. 5, with the parts in operative or expanded position;

Fig. 2 is a section similar to that shown in Fig. 1, but taken on line 2—2, Fig. 6, and showing the parts collapsed and in the position which they occupy in passing through 90 the casing;

Fig. 3 is a side elevation of the reamer with the parts collapsed and showing how they are held in position by means of a ring;

Fig. 4 shows a side elevation of the reamer 95 as it appears in operative position, the casing shoe and part of the well being shown in section;

Fig. 5 is a section taken on line 5—5, Fig. 1;

Fig. 6 is a section taken on line 6—6, 100 Fig. 2;

Fig. 7 is a section similar to that of Fig. 1, but to a slightly larger scale and shows one of the cutter lugs removed;

Fig. 8 is a side elevation of the part shown 105 in Fig. 7, but with parts broken away;

Fig. 9 is a bottom plan view looking in the direction of the arrow 9 in Fig. 7, but showing the two cutters in place; and

Fig. 10 is a section taken on line 10—10, 110 Fig. 7.

The same reference numbers will be used

to designate the same parts throughout the several views.

Numeral 1 represents what I will designate as the body member of my reamer which is a cylindrical steel bar of the proper diameter provided at one end with a threaded lug 2. The body member is provided with an axial opening 3 which receives the locking device 4 which consists of a rod having a central portion 5 of a diameter which permits it to slide freely in the opening 3. The upper end 6 is of a smaller diameter and passes through a coil spring 7 whose outside diameter is such that it can freely slide in the opening 3. Secured to the very end of the part 6 is a round nut 8 which may be held from rotation by a rivet or other suitable means. At the point of juncture between the parts 5 and 6 there is a shoulder 9. The spring 7 abuts its ends against the nut 8 and the shoulder 9. The lower end of the part 5 is slightly tapered and terminates in a wide flattened portion 10 having a head 11 which serves to hold the cutters in operative position. The portion 6 is provided with a transverse slot 12 near the shoulder 9 and the body member is provided with a corresponding slot 13. A key 14 is inserted through these slots and the spring 7 rests thereon so that the tension thereof tends to move the locking device upwardly. The key 14 has a lug 15 which engages the walls of the opening 3 and prevents the key from sliding out. A short distance below the slot 12 is a slot 16 for the reception of a key 17 which slides in a slot 18 in the body member 1. On diametrically opposite sides of the member 1 and in the plane of the key 17, I provide grooves 19 for the reception of slides 20. The bottoms of the grooves 19 are curved somewhat as shown in Figs. 1 and 2 and the inner edges of the slides are similarly curved. The slides 20 have corners or shoulders 21 which project out beyond the surface of the cylinder a distance of one-half inch or more when the parts are in the position shown in Fig. 1, the distance from the tip of one shoulder 21 to the other exceeding the diameter of the casing. When the slides 20 are moved downwardly to the position shown in Fig. 2, they will, of course, move the key 17 and the locking device in a downward direction compressing the spring 7 slightly during this movement. As the slides move downwardly in the slots 19, the shoulders 21 move towards each other, due to the inclined surfaces referred to. By the simple expedient of slipping a ring 22 over the slides in the manner shown in Fig. 2 they will be held from moving back. The ring 22 has an internal diameter substantially equal to that of the casing and has an opening (not shown) so that it may be removed from about the cable after it has served its purpose. When the parts are in collapsed

position, like that shown in Figs. 2 and 3, the reamer may be inserted into the casing and as the top of the casing strikes the ring 22, the latter is shoved off from the slides and the inside of the casing substituted therefor. To the lower end of the body member are secured two cutters 23 and 24 which are pivoted to the pins 25. The end 26 of the cutter is curved on the arc of a circle concentric with the pivot pin 25 and the surface of the body member is similarly curved at the same radius so that as the cutters move about their pivots, their ends will slide on the curved surface and be in contact therewith and therefore any endwise force will not have to be resisted by the pins 25, but will be taken up by the surfaces at 26. The lower ends of the cutters are provided with cutting heads 27 which are shaped somewhat as shown in Figs. 7 and 9, their outer edges being curved on the arc of a circle whose diameter is equal to the diameter of the hole to be reamed. Owing to the fact that the cutting heads are subjected to the action of grit and sand, which wears them away very rapidly, they are made with removable wearing shoes 28. These shoes are made of hard steel properly tempered and are secured by means of dove-tailed portions 29 which cooperate with a similarly shaped groove in the head 27, all as shown and described in my co-pending application, Serial No. 603,324, filed November 25, 1922. The heads 27 have shoulders 30 which contact with the ends 31 of the body member so that the shocks experienced during operation are resisted by the surfaces of the shoulders, as well as the ends 26. This makes the parts almost as strong as if they were forged from a solid piece.

The cutters carry lugs 32 on their inner sides and these cooperate with the cavities 33 in the body member and resist any force that tends to pull the cutters out of the holder and which might otherwise shear 110 the pins 25. When the reamer is inserted into and removed from the casing, the cutters slide along the inside of the casing and are constructed with outwardly curved portions 34 of hardened steel which are held in place in dovetail shaped transverse grooves. These wearing shoes may be replaced when they become too badly worn and in this manner the cutter may be used for a much longer time. In fact, by replacing the cutter shoe 28 and the wear shoe 34, the remaining portions of the cutter may be used indefinitely. The cutters are held in expanded position by means of the head 11 which forms the bottom portion 115 of the locking device. This head is of such width that it fits snugly between the inner surfaces of the cutters in the manner shown in Figs. 1, 4 and 9, and has its sides curved 120 in the manner indicated by the numeral 35 130

in Fig. 9. The edges of the curved sides 35 extend beyond the flat sides of the head 11 and form shoulders 36 which embrace the sides of the cutters in the manner shown in Fig. 9 and prevent the shoes 28 from sliding in the grooves. The lower end of the locking device carries two springs 37 which engage with the inner surface of the cutters and tends to move them outwardly into operative position. When the parts are collapsed as shown in Figs. 2 and 3, the springs 37 will hold the cutters spread so that they must be held in collapsed position by some means, (not shown), while the reamer is inserted into the casing. The slides 20 have shoulders 38 and are held in place by means of removable plates 39, (Fig. 5).

The reamer being assembled and constructed in the manner described, operates in the following manner:

The parts normally assume the position shown in Figs. 1, 4 and 7 in which position it is, of course, impossible to insert the reamer into a casing of the size used in a well of the diameter for which the reamer is made. Before the reamer can be inserted in the casing, the parts must be moved into the position shown in Figs. 2 and 3. This is accomplished by moving the slides 20 downwardly against the key 17 until the head 11 projects below the cutter surfaces 28. A ring 22 is then put into place in the manner shown in Fig. 3 and this prevents the slides from moving back and consequently holds the locking device in the inoperative position. In order to insert the end of the reamer into the casing, the lugs 23 and 24 must be moved inwardly against the action of the springs 37 and held in this position until they are inserted in the casing. This can be done by hand. When the reamer has been lowered until the ring strikes the upper end of the casing, the ring is forced to remain.

When the end of the reamer emerges from the casing, the springs 37 will move the cutters into open position and when the slides 20 emerge the spring 7 will function and pull the head 11 up into locking position, shown in Figs. 1, 4 and 7. It is evident that when the parts are in operative position, the cutters will be positively held against collapsing and at the same time the head 11 and the curved sides 35 will prevent mud from entering into the reamer body.

When it is desired to remove the reamer,

it is merely necessary to pull the same upwardly into the casing. The projecting lugs 40 serve to center the reamer in the casing and as the shoulders 21 of the slides 20 strike the lower edge of the casing shoe 41, they will move downwardly, forcing the locking device out of locking position so that when the cutters reach the casing, they are free to move inwardly into the position shown in Fig. 3.

Having now described my invention, what I claim as new is:

1. An under - reamer comprising a body member having an axial opening; a locking device in said opening, said device having a portion of reduced diameter; a spring surrounding said reduced portion; a key slot in the body member and in the locking device; a key passing through said slot and forming an abutment for the spring; a second key slot in said locking device; a key slot in the body member, a key passing through said slots; a sliding member on each side of the body member, said sliding members engaging the ends of the last named key and adapted to move the same and to cause the locking device to be moved against the tension of the spring, a pair of diametrically opposed cutters pivotally connected to the body member and a head on the end of the locking device adapted to engage between the cutters to hold the same in operative position.

2. An under - reamer comprising, in combination, a body member having a longitudinal opening; a locking device in said opening; a key passing through the body member and the locking device, said locking device being slidable with respect to said key; a spring abutting said key and adapted to hold the locking device in retracted position; a second key projecting through the body member and through the locking device, said key having a longitudinal movement with respect to the body member; slides secured in grooves in each side of the body member and adapted to engage the ends of said key, said slides having portions projecting beyond the outside of said body member; a plurality of cutters pivotally connected to the body member; and a locking head on the locking device, said head being adapted to fit between the cutters when they are in expanded position.

In testimony whereof I affix my signature.
WILLIAM R. WILBER.
